UNITED STATES PATENT OFFICE

2,522,111

COMBINED ERASING SHIELD AND
PROTECTOR

Frederic H. Gibson, Westwood, N. J.

Application April 5, 1948, Serial No. 18,965

3 Claims. (Cl. 120—41)

1

The improvements relate to means for making erasures in written or typewritten matter, sketches, drawings and the like without disturbing adjacent matter not intended to be erased, protecting the paper or the like on which the erasure is to be made, and providing for a single instrument which may be used where there are original and carbon copies whereby erasure on the original or topmost carbon does not mark or smudge the subsequent copies.

This invention is in the nature of an improvement on my copending application Serial Number 740,801, filed April 11, 1947.

One of the objects of this invention is to provide a readily accessible and compact protecting plate, eraser and guide which may be quickly inserted between sheets on the platen of a typewriting machine or removed therefrom in order to make specific erasures without affecting the sheets or rest of the typewritten matter.

Another object of the invention is to provide a combination erasure shield, guide and backing plate whereby when an erasure is to be made the device may be easily slipped into place and an erasure made without allowing the effect of the erasure to appear on carbon copies beneath or near the point at which the erasure is made.

Another object of the invention is to provide a combination eraser, erasing shield and erasing shield holder which may be kept easily accessible and as a compact unit. Other objects and advantages will be apparent from the following description and the accompanying drawings referred to therein.

Referring to said drawing:

Fig. 1 is a perspective of the protecting plate erasure shield, eraser and handle;

Fig. 2 is an enlarged vertical cross section on the line 2—2 of Figure 1.

Referring to the drawing, 1 is an arm made of sheet plastic or light metal. 2 is a second arm made of a similar material. The arms 1 and 2 are joined at 3 by a suitable fastening device shown as a rivet 4 passed through their overlapping ends. Adjacent to the point of joinder 3 is placed a spring member 5 for the purpose of normally holding the arms 1 and 2 slightly apart except when they are purposely pressed together. This spring member 5 may also be made of a light metal or plastic and joined to the arms 1 and 2 at 6 by glue or other fastening means or by fusing or spot welding.

The arm 1 has rigidly fastened to it at the opposite end from the aforesaid joinder 3, a shield 7 which is rigidly fixed to the arm 1 by

2

means of rivets 8 and 9 or other suitable securing means.

The arm 2 has rigidly fixed to it at the opposite end from the aforesaid joinder 3, an erasing shield 10 which is affixed by means of the rivets 11 and 12 or other suitable means. The erasing shield 10 has cut into its lower portion the usual apertures such as 13, 14, 15 and 16 for placement over the letters, marks or words to be erased.

Shield 10 has affixed on the side which is attached to the arm 2 the socket member of a snap fastener 17 or the like whose complementary stud portion 18 is attached to an eraser 19 as shown and described in my said copending application.

In the preferred form of this invention, the arms 1 and 2 are of metal, plastic or other durable resilient material of a thickness of approximately .040th inch while the protecting plate and erasure plate are preferably of a thickness of .010 inch, although these thicknesses may be varied to a considerable extent. The purpose of having a thin but tough erasure shield and protective shield is primarily to allow the shield to be placed between a sheet or sheets of paper in a typewriter and yet allow the two erasing and protecting shields 1 and 2 to accommodate themselves to the contour of the typewriter platen.

In operation, when it is desired to erase a letter or word the operator using the arms 1 and 2 slips the erasing shield and protective shield over the upper sheet in the typewriter so that the sheet on which the erasure is to be made is between the erasing shield 10 and the protective shield 7 and the protective shield is between the sheet upon which the erasure is to be made and the carbon sheet by which the copy is made. The erasure shield is then adjusted so that one of the apertures 13, 14, 15 or 16 is over the matter to be erased, and at any point lengthwise or crosswise of the sheet. The operator now unsnaps the eraser 19 and makes the erasure through the correct aperture. Erasures may now be made over any carbon copies in the same manner and when completed the eraser 19 is again snapped onto its complementary button ready for the next operation.

It will be noted that the protecting shield 7 and the erasure shield 10 are offset laterally from the length of the arms 1 and 2. This construction is necessary so that the operator may easily avoid any obstructions at the side of the typewriter.

In the preferred form shown by the drawing, I have shown the arms 1 and 2 made of two separate strips of material although I do not limit myself to this feature, as it is possible to make the arms of a single piece bent in the middle and held tightly separated by the spring member 5 or by their own resiliency. If the material connecting the flexible plates 7 and 10 is made of a tapered or spring-like substance such as thin steel, it is possible to eliminate the spring member 5 entirely as the natural spring of the connecting piece will have a tendency to hold the plates 7 and 10 slightly apart.

Various other modifications in the details of construction of the exemplary embodiment shown and described may also be made without departing from the scope or purview of the invention.

What I claim is:

1. In a device of the character described a plate of thin flexible material having apertures therein through which erasures may be made, a relatively rigid arm affixed to said apertured plate, a second plate of thin flexible material, a relatively rigid arm to which said second plate is connected, said arms extending from said plates being joined together at a point distant from the plates so that said apertured plate may be superposed over said second plate and a spring member between said arms near their junction by which they are normally separated.

2. In a device of the character described, a plate of thin flexible material having apertures therein through which erasures may be made, a thin relatively rigid arm rigidly affixed to said apertured plate, a second plate of thin flexible

material, a thin relatively rigid arm connected thereto, said arms being joined at an angular displacement and said plates being offset laterally from said arms and joined together at one end by a spring member by which said plates are normally held separated.

3. In a device of the character described, a plate of thin flexible material having apertures therein through which erasures may be made, a relatively rigid arm affixed to said apertured plate, a second and coincident plate of thin flexible material and a second relatively rigid arm to which it is connected, each of said plates affixed to its said arm so that the bottom of the said plate and the top of said arm is in angular displacement, said arms extending to a point distant from said plates and being joined together at a distance from said plates so that said apertured plate may be superposed over said second plate, said plates and arms being normally otherwise separated from one another and held apart by a spring member, whereby a plate and arm may be placed one on each side of a sheet on which an erasure is to be made without disturbing said sheet.

FREDERIC H. GIBSON.
